tion, New York, N. Y., a corporation of New
York

Application January 15, 1946, Serial No. 641,324

9 Claims. (Cl. 101—93)

1

This invention relates to tabulating machines and more particularly to improvements in the printing mechanisms therefor.

The principal object of the invention is to provide an improved printing mechanism for printing alphabetic characters as well as digits, in which the type characters are moved into printing position and then restored to a home or rest position, in a positive manner.

In printing machines to which the present invention applies and of which United States Patents 2,016,682 and 2,056,391 are examples, a bank of vertically reciprocable type carriers is provided, each carrier having a multiplicity of type elements which, when the carrier is elevated, pass in succession through a printing position opposite a platen. A so-called cross-head is usually provided which in the earlier Patent 2,016,682 draws the carriers upward through the medium of a spring connection. During such upward movement, which is generally at a uniform rate, a dog or latch is interposed in the path of the carrier to stop it at a selected type position. Such stopping is effected while the type carrier is in rapid motion, so that the stopping is effected with some shock due to the sudden interruption of its upward movement.

In the later Patent 2,056,391, the type carriers are normally disconnected from the cross-head which makes an invariable reciprocation, moving upwardly with a rapid uniform motion. During this upward movement, the type carrier is coupled to the cross-head at differential times, so that it is suddenly accelerated from a rest position to the speed of movement of the cross-head. This, too, incurs incidental shock which is a limiting factor to high speed operation of such type of printing mechanism.

In accordance with the present invention, the single cross-head of the prior machines is replaced by a series of separately reciprocated cross-heads, each of which has a different extent of movement and moves upwardly from a rest position with gradual acceleration, reaches its limit of movement with a gradual deceleration, comes to rest, and then reverses its movement to accelerate slowly as it returns and decelerates slowly again as it reaches its initial position.

Coupling devices are provided to selectively and positively couple any type carrier to any of the cross-heads, when the latter are at rest, so that thereby the coupled carrier is moved upwardly with gradual acceleration for an extent determined by the cross-head selected and brought to rest with gradually decelerated motion

2

to present a type element at the printing position.

By providing ten such cross-heads, each carrier is positionable in any one of ten different printing positions to print any of the ten digits.

For printing alphabetic or other characters, type elements are displaceable on the carrier one or more steps to present type located intermediate the digit type. This is effected by providing a so-called zone bar which is differentially positioned in any of four vertical positions through a separate set of four cross-heads, each of which is movable in the same manner as the first set, each to one of four different positions, i. e. with a gradually accelerated starting and stopping motion.

With this arrangement there is provided a high speed printing mechanism in which the shock of starting and stopping the movement of the type carriers is eliminated and quieter and smoother operation is attained.

A more specific object of the invention resides in the provision of novel coupling devices for connecting a type carrier to its actuating cross-head for positive movement thereby in either direction of movement.

Other objects of the invention will be pointed out in the following description and claims and illustrated in the accompanying drawings, which disclose, by way of example, the principle of the invention and the best mode, which has been contemplated, of applying that principle.

In the drawings:

Figs. 1 and 2 taken together and joined at the broken line across the bottom of Fig. 1 and top of Fig. 2 constitute a sectional elevation through the apparatus in the plane of one of the carriers.

Fig. 3 is a view similar to Fig. 1 showing the parts in a type selecting position.

Fig. 4 is a time chart showing the relative extents of movement of the several cross-heads and the manner of their movement during a cycle of operation.

Fig. 5 is an end elevation taken substantially along the lines 5—5 of Figs. 1 and 2.

Referring to Fig. 1, each type carrier 10, of which there are a plurality arranged side by side as indicated in Fig. 5, is vertically reciprocable in guide combs 11 and has pivoted thereon a gear 12 which meshes on one side with rack teeth 13 in a type head 14. Head 14 is slidable on carrier 10 by means of blocks 15 integral with the head and slidable in a slot 16 in the carrier.

The other side of gear 12 meshes with rack teeth 17 in a zone bar 18, which latter is guided for vertical movement in comb guides 19 and

normally held in its upper extreme position by a spring 20 acting on a lever 21 pivoted to the bar and to a rod 22. Type head 14 contains a plurality of type elements 23 which are movable upwardly past printing platen 24 to present any element thereto for printing.

There is shown in Fig. 1 a diagrammatic representation of the well known record card sensing mechanism comprising feed rollers 25 which move record card 26 past a row of sensing brushes 27 and a contact roller 28 at a uniform rate, so that perforation receiving positions arranged in rows designated 9, 8, 7, 6, 5, 4, 3, 2, 1, 0, 11 and 12 are sensed in succession. A perforation in row 9 represents the digit 9, a perforation in row 8 represents the digit 8 and so on. To represent alphabetic or other characters, a vertical row is punched in one of the digit positions 9 to 2 in accompaniment with a second or zone perforation in one of the positions 1, 0, 11 or 12. For each digit representing perforation and for each combinational perforation, there is provided a type element 23 arranged on the type head and identified as indicated in the diagram at the left of the type elements in Fig. 1. Here it is noted that between each digit representing type 1 to 9 there are four combination representing type the manner of whose selection will presently be explained.

On each carrier 10 is pivoted a bell crank 30 and a latch 31 connected together by a link 32. A spring 33 serves to hold the parts in the positions shown in Fig. 1, where the end of latch 31 engages in a notch in a bell crank 34 to hold the latter in position. Below bell crank 34 is a lever 35 also pivoted on the carrier and urged in a clockwise direction by a spring 36. When the carrier is in its rest or restored position as shown, the contacting ends of levers 34 and 35 are held to the left of the right edge of carrier 10 and a depending arm of bell crank 30 lies in line with a tripping pawl 37 to hold the pawl in the position shown.

Adjacent to lever 35 are ten cross-heads separately numbered 9 to 0 with the uppermost cross-head designated 9 lying opposite the junction of levers 34, 35 and a line which may be identified as a base line 41. The cross-heads 40 are nested as shown and suitably guided for vertical reciprocation. Each cross-head has a link 42 (Fig. 2) hook-shaped at its upper end and engaging a roller 42a (see Fig. 5) carried by the crosshead. The lower end of link 42 is also hook-shaped to partially encircle the rounded end 43a of an arm 43 which is free to oscillate on a shaft 50. Thus, there are ten arms 43 (Fig. 5) and each has a follower lever 44 (Fig. 2) whose roller 45 cooperates with a pair of complementary cams 46. These cams, of which there is a differently configured pair for each lever 44, are secured on shafts 47 driven through gears 48 from shaft 50. Shaft 50 is geared to the card feed rollers 25 (Fig. 1) through connections not shown, so that a card 26 is fed past the brushes 27 for each revolution of shafts 50 and 47 with the hole positions 9, 8, 7, etc. passing brushes 27 at the same points in successive cycles as is well known.

The relative timing of the cross-heads 40 and sensing points of brushes 27 is diagrammatically represented in Fig. 4, where the timing is given for a cycle of operation. In this diagram along the line designated "Sensing Brushes 27" the points or periods in the cycle when the several perforation positions are at the row of

brushes 27, are indicated by short regularly spaced horizontal lines. The cross-head base line 41 is also indicated with the 9 cross-head designated as standing at this line at the commencement of the cycle. Between the 9 and 8 sensing times the 9 cross-head gradually accelerates as represented by the beginning of a graph 51, and during the same period the 8 cross-head 40 moves up to the base line 41 where it is at rest during the 8 sensing time, and then it gradually accelerates upwardly as indicated by graph 52.

In succession thereafter, each remaining cross-head 40 moves from its restored position below base line 41 up to the line, arriving there and stopping during the period that the correspondingly numbered sensing position is passing the sensing brush 27. Near the midpoint of the cycle, the several cross-heads 40 will have been elevated to differently spaced positions with the 9 cross-head advancing the farthest distance and the 0 cross-head advancing the least distance. In other words, the cross-heads have "fanned out" from their close initial spacing to an extended spacing.

The sensing of a perforation at any of the 9 to 0 positions will cause a carrier 10 associated with the columnar position of the sensing brush 27 to become coupled to the related cross-head 40 and carried upward therewith. For example, let it be assumed that there is a perforation in the 9 position in a card column. Then (in Fig. 1) at the 9 time a circuit is completed as indicated in a simple manner from a negative side 30 of a source of current, through contact roller 28, 35 9 hole in the card, brush 27, a magnet 55, to positive side of the current source. This energization occurs at the 9 time in the cycle (Fig. 4) when the 9 cross-head 40 is at rest. As a result, magnet 55 attracts its spring biased armature 56 to shift pawl 37 to the left (Fig. 1) to rock bell crank 30, and through link 32 rock lever 31 likewise. Thereupon, spring 36 will rock levers 34, 35 oppositely, to the position of Fig. 3, where they 45 grasp the upper edge of the 9 cross-head. Lever 31 then engages a notch in lever 34 to detent the parts in cross-head engaging position. It is thus seen in Fig. 3 that lever 34 is locked against clockwise rotation and its lower extremity is accordingly held in position overlying the left edge 50 of crosshead 40. At the same time lever 35 extends under the left edge of the crosshead where it is resiliently held by spring 36. The crosshead is accordingly grasped by the fingers in such a 55 manner that the carrier must move upwardly therewith in a positive manner. As the 9 cross-head 40 thereafter rises, carrier 10 moves with it to the position of Fig. 3. As the carrier rises, its gear 12 rolls on rack teeth 17 and as a result type head 14 is elevated at twice the rate of the carrier and to twice the extent to present the 9 type element 23 in printing position opposite platen 24.

To illustrate further, assume a perforation in the 2 position in a card column. Then at the time this hole is sensed, the related cross-head 40 (designated "2 Hole" in Fig. 2) will be at the base line 41 and the circuit to magnet 55 at such time will cause coupling of the carrier to the 2 cross-head, and thereafter will be gradually elevated thereby to the extent of movement of this cross-head to a position where the 2 type element 23 is positioned for printing.

While the cross-heads are at rest in their uppermost positions during the period designated

"Printing Time" in Fig. 4, an impression is taken from the presented type elements through the usual mechanism (not shown), and thereafter the cross-heads are restored as indicated in the diagram with gradual acceleration and deceleration.

Referring to Fig. 2, a bail 58 extends across through openings in the carriers 10 and, as the cross-heads approach their home position, this bail is elevated by a cam 60 on shaft 47, through follower bell crank 61 and link 62, so that its upper edge will intercept the horizontal arm of lever 34 just before the carrier reaches its home position to rock the levers 34, 35 out of engagement with the connected cross-head and arrest the carrier in home position, where latch 31 will hold the levers 34, 35 retracted. The lower end of link 62 is bifurcated to straddle bail 58, so that as the link is elevated, the bail moves likewise and its upper edge rises a distance in Fig. 2 to bring such edge up to the horizontal arm of lever 34. Obviously, with the bail in such upper position, as the lever 34 descends in the relative position it occupies in Fig. 3 it will strike the elevated bail edge and be rocked back to the position of Fig. 2. The period during which bail 58 is elevated is represented in Fig. 4, where it is seen that at the end of the cycle the bail is lowered, so that the parts will be rendered responsive to the sensing of a perforation in the next cycle.

The foregoing explains the manner of operation of the device for the selection of the characters 9 to 0 in response to the sensing of a single perforation in one of the related positions of a card column. The manner in which combinationaly represented characters are selected will now be explained.

Zone bar 18 (Fig. 1) has pivoted thereon a pair of cross-head engaging levers 63, 64 held out of engaging position as shown by a pivoted latch 66. The upper end of this latch is in line with a notch 37a in pawl 37 so that, when magnet 55 is energized with pawl 37 in the full line position, latch 66 is not disturbed.

It will be noted that bell crank 30 is provided with a latching projection engaging the upper edge of pawl 37 to hold the pawl in its full line position against the tension of spring 80. Thus when magnet 55 is energized in response to a hole in any card position from 9 to 1 latch 30 will be rocked and latched in rocked position as explained so that pawl 37 when subsequently retracted upon deenergization of magnet 55 will be rocked clockwise by spring 80 to its upper dotted line position in which projection 37b will be in line with the upper end of latch 66. If there is now a second energization of magnet 55 in response to a hole in the 1 or 0 positions, latch 66 will be rocked counterclockwise to release levers 63, 64 for engagement with one of the cross-heads 72.

Alongside levers 63, 64 are four cross-heads 72 designated 1, 0, 11 and 12 mounted for reciprocation similarly to cross-heads 40 with the 1 cross-head normally lying on what may be called a zone base line 73. Through links 74 (Fig. 2) and levers 75 these cross-heads are reciprocated by cams on shafts 47 which are similar to cams 46 but configured to move the cross-heads 72 as indicated by the lines 76 in Fig. 4, so that each is in turn at rest on the zone base line 73, at the time of sensing the related characters 1, 0, 11, or 12. Thus the zone bar 18 is selectively coupled to one of the cross-heads 72 for gradually ac-

celerated downward movement for the extent of movement of the connected cross-head.

Such downward movement of bar 18 will turn gear 12 to raise type head 14 one, two, three or four type spaces to select the combination representing type elements 23 intermediate the type selected directly by carrier 10.

A bail 67 extending across and above pawl 37 is pivoted at 68 and has link connection 69 with a cam follower 70. Under control of a cam 71 (Fig. 2) on shaft 47, bail 67 will be depressed to lower pawl 37 to its lower dotted line position of Fig. 1 wherein edge 37c of a notch in the under side of the pawl lies adjacent to the upper end of latch 66. This shifting of bail 67 and pawl 37 occurs after the 0 hole position on the card has been sensed and before the 11 hole is sensed as indicated in Fig. 4.

Thus if an 11 or 12 hole is sensed and magnet 55 is energized in response thereto, edge 37c will rock latch 66 so that levers 63, 64 engage the 11 or 12 cross-head 72 for movement thereby.

These zone cross-heads 72 are held in their extreme positions during the printing time and are then restored as indicated in Fig. 4. A bail 59 connected through a link 78 and a pivoted lever 79 to follower 61 is lowered under control of cam 60, so that as each pair of levers 63, 64 returns to the start position, it will be retracted and relatched in the same manner as levers 34, 35 near the end of the cycle.

In Fig. 3 the parts are shown at the printing time with the carrier 10 coupled to the 9 cross-head 40 and the zone bar 18 coupled to the 1 cross-head 72 resulting in the presentation of the type element 23, with the character assigned to the combination of 9 and 1, to the platen for printing. As seen from Fig. 1, this involves movement of the 9 representing element 23 to the platen under control of carrier 10 and the further elevation of head 14 by the zone bar 18 four steps to bring the lowermost type element into position.

Briefly reviewing the sequence of operations, where the card column sensed contains only a single perforation, pawl 37 is in its full line position of Fig. 1 while positions 9 to 0 are sensed and a hole in any one of these positions will result in rocking of bell crank 30 and coupling of the bar 10 to the related cross-head 40 for movement directly to the appropriate printing position for the digits 9 to 0. During the sensing of the 11 and 12 positions pawl 37 is in its lower dotted line position where the pawl is out of line with bell crank 30 and the sensing of an 11 or 12 hole will cause pawl 37 to rock latch 66 through edge 37c to couple bar 18 to the 11 or 12 cross-head 72 and through gear 12 elevate bar 14 to present the 11 or 12 type 23 to the printing line.

For combinational perforations, when the first hole is one of the positions 9 to 2, bell crank 30 is tripped and moves up allowing pawl 37 to assume its upper dotted line position, so that when the second hole in either of the positions 1 or 0 is sensed, extension 37a will trip latch 66. When the second hole is in either the 11 or 12 position edge 37c will trip latch 66 since at such time the pawl 37 will be in its lower dotted position.

For the combination 1-0, 1-11, 1-12, the 1 hole will trip bell crank 30 with pawl 37 in full line position, and thereafter for 0, latch 66 will be tripped by projection 37b. For the 11 and

12 holes, pawl 37 will be in its lower dotted position and latch 66 will be tripped by edge 37c.

For the combinations 0-11, 0-12, the 0 hole will trip bell crank 38 with pawl 37 in full line position and thereafter pawl 37 is shifted to its lower dotted line position so that the subsequent 11 or 12 holes will cause edge 37c to trip latch 66.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a printing machine, a type bar mounted for reciprocating movement, a plurality of cross-heads each movable a different extent in the direction of reciprocation of the type bar, means for moving each cross-head from a position of rest with gradual acceleration and advancing it to the limit of its movement with gradual deceleration, and means for selectively coupling the type bar to any one of said cross-heads while the cross-head is at rest, whereby the type bar will be advanced to a selected printing position under control of the selected cross-head.

2. In a machine of the class described having a type carrier provided with a plurality of type elements and movable from a position of rest to differential positions for printing from selected type elements, the combination of a plurality of cross-heads, means for moving each cross-head in turn to a coupling position with respect to the type carrier and momentarily arresting the movement thereof in such position, means effective when the cross-heads are in coupling position for selectively coupling the type carrier to any one thereof, said moving means being effective to move the cross-heads in turn from the coupling position with gradual acceleration each to a different extent, whereby the carrier will be differentially advanced with gradually accelerated motion from rest position to a selected printing position.

3. In a machine of the class described having a type carrier provided with a plurality of type elements and movable from a position of rest to differential positions for printing from selected type elements, the combination of a plurality of parallel cross-heads normally spaced apart a predetermined distance in the direction of movement of the type carrier, means for moving said cross-heads in the same direction to ultimate positions wherein they are spaced a distance apart greater than said predetermined distance, and means for selectively coupling the carrier to any one of the cross-heads for movement thereby from the carrier's rest position to the cross-head's ultimate position.

4. The invention set forth in claim 3 in which

said moving means comprises means for starting the movement of said cross-heads each with a gradually accelerated motion.

5. The invention set forth in claim 3 in which said moving means comprises means for starting the movement of said cross-heads each with a gradually accelerated motion and for stopping the movement of said cross-heads each in its ultimate position with a gradually decelerated motion.

10 6. In an accounting machine comprising in combination a movable type carrier having a plurality of type elements thereon, a plurality of moving devices for said carrier, each operable through a different extent of movement, operating means therefor to move each device with a gradually accelerated motion for part of its related extent of movement, card sensing means, and means controlled thereby for coupling the carrier to a selected one of said devices for movement thereby to the related extent.

15 7. The invention set forth in claim 6 in which the coupling means is arranged for engaging the selected moving devices for positive movement thereby.

20 8. In a machine of the class described, a type carrier movable from a rest position to a printing position, a type head comprising a plurality of groups of type slidably carried by said carrier, a first plurality of moving devices for said carrier,

25 a second plurality of moving devices for said type head, each of the first named moving devices being operable through a different extent of movement, each of the second named moving devices being also operable through different extents

30 35 of movement, operating means for the moving devices to move each device with a gradually accelerated motion for part of its extent of movement, means for selectively coupling said carrier to one of the said first devices and further coupling means for selectively coupling the type head to one of said second moving devices whereby a selected type element on the type head will be positioned for printing.

40 45 9. The invention set forth in claim 8 in which means is provided for causing the two coupling means to be operated in succession.
